DEVICE FOR PROTECTING SHIPS AGAINST TORPEDOES

Awksenty J. Sinchuk, Bridgeport, Conn.

Application June 6, 1942, Serial No. 446,127

3 Claims. (Cl. 114—240)

My invention relates to anti-torpedo devices and has particular reference to devices for protecting ships against torpedo attacks.

My invention has for its object to provide means to protect moving ships against submarine attacks and, generally, against attacks by torpedoes, whether launched from submarines, other warships, or from torpedo carrying planes.

The most effective devices for protecting ships against torpedo attacks are nets, suspended in water at a distance from the hull of a ship. Such nets, however, are not suitable for use with moving ships because of their great resistance to motion in water.

I propose to use torpedo destroying or catching nets of relatively small dimensions, movably supported at a certain distance from the board of a ship and suspended in the air so that they cannot impede the ship movement. Suitable mechanisms are provided for quickly bringing the net or nets into the path of an oncoming torpedo and to submerge the net. The net may be so constructed that it will absorb the shock of the impact of the torpedo, so that the latter will be harmlessly caught in the net, to be used again, this time against the enemy.

Several such nets can be placed on suitable rails along the hull of the ship, to be electrically operated from a central control point. The nets may be further folded against the side of the ship when the latter is sailing in a zone safe from enemy attacks.

Another object of my invention is to provide a listening device at the end of the net to facilitate detection of a coming torpedo and to give warning to the control officer to enable the latter to place the net or nets directly in the path of the torpedo.

Still another object of my invention is to provide means to keep the net at a constant depth of submergence when the ship is rolling on waves.

My invention is more fully described in the accompanying specification and drawing in which—

Fig. 1 is an elevational view of my device, shown in a position, ready to be lowered into the water. Other positions are shown in dotted lines, i. e.; an operative position, with the net fully submerged, and an inoperative position, with the net and its supporting arms folded against the side of the ship;

Fig. 2 is a top plan view of the same;

Fig. 3 is a front view of the same, partly in action;

Fig. 4 is a plan view on a reduced scale of a ship with my protective devices.

My device for protecting ships against torpedoes consists of a main net 1, preferably made of a resilient steel wire so that it can be deflected when struck by a torpedo, thereby damping the shock and preventing explosion of the torpedo.

The net, at the same time, is sufficiently strong to prevent the torpedo from reaching the board of the ship, even if the torpedo actually explodes on contact with the net. To protect the ship in such an event, a horizontally disposed net 2 is added for catching the fragments of the torpedo. The main net is supported in a strong frame 3, a similar frame 4 being provided for the horizontal net 2. An additional lighter net 5 may be provided in front of the main net, still further to reduce the shock and to help to enmesh the torpedo in the nets. A safety back plate 6 is also provided at a distance from the main net, to explode the torpedo if the latter succeeds in breaking through the two front nets.

The nets are supported on outer arms 7, hinged at 8 to inner arms 9, the latter being hinged at 10 to a carriage 11. The latter has rollers 12, slidably supported on vertical rails 13, mounted on a main carriage 14. A frictional brake plate 15 with a spring 16 is provided for preventing violent movement of the small carriage up and down when the nets are actuated by the waves. Guy wires 17 extend to the outer bars from the small carriage for steadyng the nets against side movements.

For raising and lowering the nets a small winch 18 is provided on the small carriage, operated by an electric motor 19. A wire or cable 20 extends from the winch to a cross-bar 21 connecting together the outer bars.

The nets are held in readiness, as shown in full lines in Fig. 1, when the ship is sailing in a danger zone. The lowered position of the nets is shown in dotted lines. A float 22 is provided for keeping the nets in a correct position, with the horizontal net on the surface of water. The cable 20 is then loosened so that the nets can move up and down on the waves and when the boat rolls from side to side, thereby insuring the proper operative position of the nets at all times. A torpedo listening device, such as a microphone 23, may be provided at the front of the nets for detecting the noise of approaching torpedoes.

The main or large carriage 14 is supported by rollers 24 on rails 25, extending along the side of the ship 26, preferably at both sides. A number of such carriages may be provided, preferably two at each side, so that they can be quickly

moved to a desired spot in the path of an approaching torpedo. The carriages are connected to a cable 27, one at each side, the cable being operated by a suitable winch (not shown) for rapidly moving the carriages back and forth. Both carriages can be moved at the same time, or each carriage may be provided with a separate cable.

The nets can be folded against the side of the ship when the latter is away from a danger zone, the folded position being shown in dotted lines in Fig. 1.

Hinged nets may be added to the top net, operated by the torpedo itself, for closing around the torpedo and thereby catching the same.

It is understood that my device may be modified without departing from the spirit of my invention as set forth in the appended claims.

I claim as my invention:

1. A device for protecting ships against torpedoes, comprising a relatively small net, means to support the net above the surface of water at the side of a ship, means to move the net vertically downward into the water, means to move the net along the shipboard for placing the net in the path of a coming torpedo, and a second net extending horizontally outwardly from the top of the vertical net, the horizontal net being adapted to rest at the surface of water.

2. A device for protecting a ship against torpedoes comprising a rigid board, means to support the board under water in a substantially vertical position at a distance from the board

5 of the ship, a horizontal frame extending forward from the upper edge of the first frame, front and rear frames rigidly supported at the front and rear sides of the boards and at a distance therefrom, and wire nets stretched in the frames.

10 3. A device for protecting a ship against torpedo attacks comprising a carriage, means to movably support the carriage at the side of the ship, articulated arms extending outward from the carriage, a rigid frame supported approximately vertically at the ends of the arms, a wire net stretched in the frame, a second frame extending outward substantially horizontally from the upper edge of the vertical frame, a wire net

15 stretched in the horizontal frame, a float at the upper edge of the vertical frame for supporting the vertical frame submerged in water and the horizontal frame extending at the surface of water, means to move the carriage vertically at

20 the board of the ship, and means to move the carriage horizontally along the board of the ship.

AWKSENTY J. SINCHUK.
